BINDER

Herman Fabry, Evanston, Ill.

Application May 8, 1939, Serial No. 272,407

3 Claims. (Cl. 281—19)

My invention relates to binders for loose leaf sheets, and particularly those utilizing the so-called plastic binding. This binding consists of a length of flexible material bent into tubular form, a portion of the material being cut away to provide a series of fingers that engage with perforations in the sheets to be bound.

The binding, such as described, is common and in extensive use and this invention relates to means for providing a cover or backing that will conceal the hinge element or binding and that will provide extremely simple means for holding the bound unit in the case or backing.

In binders of the type described, it is common to provide a backing or cover for the sheets that are held by the described binding but in each thereof it has been found necessary to provide rivets that project through the back edge, thus marring the appearance and adding to the construction cost. I am able to avoid this difficulty by providing a single metal member of curved cross-section, the curvature being the same as that of the plastic binding element. This metal member may readily be glued securely to the material composing the backing, the resulting structure having a curved outline or contour corresponding substantially to the natural curvature of the edge of the structure.

An important element in connection with my improved binder is the fastening or connecting device that serves to join the bound bundle to the backing or cover. This comprises a single flexible wire having an initial camber, the mounting of the wire at one end being such that the wire cannot be rotated. Thus the bend in the wire is always in the same position; that is, it extends upwardly or away from the bottom of the shallow channel or support. This is essential since the additional bend necessary to unseat the fastening could only be made upwardly or away from the floor of the strip. At its opposite end the wire has a button or head having two diameters. The portion of largest diameter is arranged to fit easily within an undercut recess in an end bracket on the support, the portion of smaller diameter being arranged to pass freely through the narrow neck of the undercut recess. Thus by slight pressure on the end of the button, the bend or camber of the wire is increased, permitting the button to be readily disengaged from the fastening. The bending of the wire accomplishes another purpose in that it insures that the contact of the binding tube is at the extreme ends only of the wire. Consequently a very great force would be required to cause suffi-

cient additional bending of the wire to disengage it from its fastening.

The invention will be more readily understood by reference to the accompanying drawing, in which:

Fig. 1 is a plan view of an open binder constructed in accordance with my invention;

Fig. 2 is a sectional view, greatly enlarged, on the line 2—2 of Fig. 1; and

Figs. 3 and 4 are sectional views, also greatly enlarged, on the lines 3—3, 4—4 of Fig. 1.

In the drawing I have indicated a number of sheets 10 which may be of any desired form, for the accommodation of photographs or otherwise, the sheets being perforated, as shown, and engaged by a so-called plastic binding member. This member is composed of flexible material such as Celluloid, having a solid portion 11 and a divided portion forming fingers 12, the member being rolled into a tube, the fingers 12 overlapping the solid portion 11. By the use of a simple tool, the tube may be expanded to enable the removal and replacement of the sheets as required.

The binder of my invention comprises a strip of substantially the length of the binding, the back 13 of the strip being arcuate in cross section and terminating in brackets 14, 15 at opposite ends. This curved strip is adapted to be glued to a leather or imitation leather cover 16, lined by a sheet 17 which overlies the metal strip. Due to the curved outline of the strip and the arrangement of the parts, the cover may be securely joined without the use of rivets that project through the binding edge.

Connected to the bracket 14 in such manner as to provide for limiting freedom of movement but so as to prevent rotation is a spring wire 18. As a preferred means for attaching and preventing rotation I provide the wire with an offset end 19 which is held in a pocket provided in the bracket 14. It will be noted by reference to Fig. 2 that the wire 18 is initially bent to lie in the position shown in the said figure; that is, with its middle portion projecting above the floor of the binding member. In this position the wire has ample space to receive the additional bend necessary to free the attaching means; there is no such space downwardly or sideways. At its opposite end the wire has a button or head having a portion 20 of large diameter and a portion 21 of smaller diameter. The bracket 15 has an undercut recess, the portion 22 being slightly larger in diameter than the large diameter of the button 20 while the portion 23 is slightly

greater in width than the small diameter 21 of the button. Normally the wire will remain in the full line position of Fig. 2 with the button engaging the bracket 15. When, however, a slight thrust is exerted on the button the camber of the wire is increased as indicated in dotted lines in Fig. 2 and the small diameter of the button will be opposite the narrow portion 23 of the recess, enabling the button to be readily disengaged from its fastening.

10 It will be noted that the curvature of the back piece 13 is substantially that of the binding tube. Thus the tube will readily seat itself in position and be maintained in a snug fit by the wire which engages the extreme ends of the tube.

15 By examining Fig. 2 it will be seen that any force exerted by the bound structure against the wire will be exerted at the two extreme ends to which point there will be no tendency to further bend the wire and practically no force will be sufficient to cause disengagement of the wire.

I claim:

20 1. In a binding means adapted to hold a plurality of sheets through perforations, and including a cover member having an attached strip provided with upstanding ends, a cambered wire adapted to receive said binding member, one end of said wire being non-rotatably attached to one upstanding end, a button fixed on the other end

25 30

of said wire adapted to be engaged with and disengaged from the other upstanding end by changing the camber of the wire.

2. In a binding means adapted to hold a plurality of sheets through perforations, and including a cover member having an attached strip provided with upstanding ends, the strip being curved in cross section to provide a conformable seat for the binding member, an upwardly cambered wire adapted to receive said binding member, one end of said wire being non-rotatably attached to one upstanding end, a button fixed on the other end of said wire adapted to be engaged with and disengaged from the other upstanding end by changing the camber of the wire.

3. In a binding means adapted to hold a plurality of sheets through perforations, and including a cover member having an attached strip provided with upstanding ends, a cambered wire adapted to receive said binding member, one end of said wire being non-rotatably attached to one upstanding end, a button fixed on the other end of said wire, the other upstanding end having an undercut recess and said button having portions of two diameters, the portion of smaller diameter being adapted to pass through the narrow portion of the recess when force is exerted longitudinally of the wire to increase the camber therein.

HERMAN FABRY.
